WINDOW SHADE

Arthur L. Thexton, Cincinnati, Ohio, assignor to
 Clopay Corporation, Cincinnati, Ohio, a corporation of Maryland

Application July 13, 1944, Serial No. 544,723

7 Claims. (Cl. 160—386)

1

This invention relates to window shades and it is directed particularly to improvements in the structure of the lower edge.

A conventional window shade has a lower edge which is hemmed to provide a pocket for receiving a stiffening slat of wood to reinforce the lower edge of the shade and prevent it from curling or buckling. This reinforced edge of the shade usually is grasped when the shade is being raised or lowered. The operator, however, does not always pull straight down; rather it is more natural for the fingers to bend the hemmed portion toward a horizontal plane where they can obtain a better purchase. This causes some of the fingers to press against the shade material just above the hem and, after a while, the material along the hem line becomes deteriorated and frequently torn or damaged. Sometimes pull cords or tassels hanging from the lower edge are utilized. If they were handled properly this damage could be avoided but, even when they are present, it is found that the ordinary householder still grasps the hemmed edge instead of pulling on the cord. Even when the shade is not damaged physically conspicuous finger marks and smudges are left at the lower portion of the shade.

Recognizing these difficulties, the principal objective of the present invention has been to provide a shade structure in which the lower edge stiffening member is removable and replaceable, whereby the stiffening member can be detached from the shade, the soiled or damaged portion of the shade cut away and the stiffening member reassociated with a fresh portion of the shade.

Briefly, in accordance with this invention the removable foundation piece for the lower shade edge is a length of material having at least one, and preferably two pairs of meeting faces, hinged with respect to one another, between which the shade material may be sandwiched after it has been wrapped around or within the length of material. In this manner a snubbing action is obtained to hold the shade material within the assembly. Thus, for instance, the stiffening strip may comprise a length of fibreboard folded twice upon itself; it is used by placing the edge of the shade between the meeting faces adjoining the first fold, then folding the shade material with the stiffening strip between the second pair of meeting faces adjoining the second hinging line. As an alternative wood or metal strips preferably having longitudinal complementary serrations at their meeting faces are hinged through cloth pieces or the like and the shade is placed first be-

2

tween the serrated faces then wrapped around the exterior of the stiffening members.

Having prepared the assembly of shade and stiffener, it is held together by means of clips at the ends and center if desirable, or by means of other suitable fasteners such as screws or cleats.

Stiffening strips of the folded paper or fibreboard type preferably have durable exterior surfaces inasmuch as they may be exposed. For instance, they may be covered with calendered or glossy paper or protected with suitable paint, varnish or fabric such that it may be washed when necessary. After the shade with this lower stiffened edge has been in use for a period of time and has become damaged or soiled the stiffening strip is detached through removal of the holding clips (and lift cord if employed), then unfolded or unhinged to separate the strip from the shade. The housewife next may cut off the soiled part of the shade material, for instance, she may sever a marginal portion of, say, four to six inches, and then reassociate the strip and shade in the manner just described. These operations take but a few moments time; the line along which the shade is cut need not be exactly straight inasmuch as the severed edge is concealed within the meeting faces of the stiffening strip. The line, of course, should be substantially horizontal or substantially lateral with respect to the shade but the cutting can be done with a scissors without dismantling the shade from its brackets on the window.

In order to permit soiled or damaged portions of shade material to be removed from time to time without shortening the shade to such a degree that it will no longer cover the full height of the window, the invention contemplates the provision of shades somewhat longer than those conventionally used, the extra length of material being wound as additional convolutions upon the shade roller. In this manner the supply of extra shade material may not be noticed yet it is available when needed.

One typical structure embodying these principles is disclosed in the drawings in which:

Figure 1 is an elevation of a shade having its one end mounted upon a shade roller and its other end having the removable stiffening strip attached thereto.

Figure 2 is a sectional elevation taken on the line 2—2 of Figure 1.

Figure 3 is a fragmentary perspective view showing the shade in the process of being folded up with the stiffening strip.

Figure 4 is a cross sectional view taken on the line 4—4 of Figure 1.

Figure 5 is a view of a modified structure showing the employment of a screw in place of a pull cord for holding the layers of the stiffening together at the central portion of the shade.

Figure 6 is a view of another modified form of structure in which a pair of stiffening strips of wood, metal, plastic or the like are hinged together, within which the shade material is 10 snubbed.

The shade roller 1 and the manner in which the shade 2 is associated with the roller may be conventional; they form no part of the present invention and, therefore, are not disclosed here in detail. The shade, designated 2 in the drawings, is rolled upon the roller through a number of convolutions and the free portion depends from the roller in the usual manner. It is to be observed as just described that the length of the shade 20 as a whole should be sufficient to cover the window area and, in addition, provide some excess which serves as a supply to compensate for portions at the other end which are removed from time to time.

The stiffening strip, indicated generally at 3, comprises a length of material commensurate with the width of the shade delineated into at least three longitudinal sections 4, 5 and 6 by means of suitable score lines 7. The sections 4, 5 and 6 preferably are of substantially equal width such that the outer sections 4 and 6 may be folded over one another without marginal protrusions. This element may be constructed of cardboard, fiberboard or other types of paperboard which are inherently stiff and rigid in longitudinal directions yet sufficiently flexible laterally to be folded without cracking. At least one surface of the strip, which later may form an outer or exposed surface, is suitably protected through an applied layer of finishing composition, glossy paper, cellophane or fabric. The exposed surface may be of the same material from which the shade is made in order that the shade and lower stiffened edge will be of uniform appearance.

For association of the stiffening strip with the shade in a typical manner one of the outer marginal portions, e. g., 6 is folded over the central section 5 in the form of a roll fold and the marginal edge of the shade material is then disposed between these sections. Next, these folded sections and shade material are folded as a unit against the shade and other section, e. g., 4. Such an operation is illustrated in Figure 3. In this manner the edge of the first folded section 6 is caused to serve as a snubber with respect to the shade material and thus prevents detachment of the shade from the "sandwich."

For a permanent installation adhesive may be applied between the layers to unite them. However, for removable association of the stiffening strip and shade material clips 8 are utilized to prevent the roll or pile from unfolding. The clips may be of U-shape to embrace the sidewise of vertical edges of the assembly as shown in Figure 1. In this position they are inconspicuous yet readily may be removed. The clips preferably are yieldable whereby they may be spread apart slightly, then slipped over the outer faces of the assembly, and released to hold the laminations one against another.

At the central portion of the shade apertures 9 may be provided in the stiffening strip, in positions for alignment with one another when the stiffening strip is folded. The apertures in the 75

outermost sections 4 and 6 may be equipped with metal grommets 10, if desirable, for additional protection. When the stiffening strip is associated with the shade a hole may be poked 5 through the shade material behind the apertures by means of a pen or pencil and the pull cord 11 can then be entered through the opening for association with the lower shade edge in the usual manner.

If a pull cord is not to be employed then a blunt screw of the type sometimes used to hold a pull cord may be employed, the threads of the screw being of relatively heavy pitch so as to find purchase in the layers of the stiffening strip.

Paperboard, fiberboard and the like readily may be folded upon itself whereby the hinged action between the meeting faces takes place along the fold lines to enable the introduction of the shade material into the roll or pile. However, the conventional type of inexpensive paperboard or fibreboard which is sufficiently thick to provide the desired longitudinal stiffness tends to crack when folded upon itself, while other types of paperboard which posses the desired foldability are 25 quite expensive. It is not necessary for the utilization of this invention that the stiffening material be foldable upon itself. Meeting faces may be hinged by supplemental means such as cloth or paper adhesively united to the foundation members. An arrangement of this sort in which a material such as wood, plastic or metal is employed because of its desirable longitudinal rigidity is shown in Figure 6.

According to this structure two strips 12 are 35 utilized. These have meeting faces containing complementary longitudinal serrations designated at 13 while the outer surfaces of the strips may be of a somewhat curved or rounded shape. These strips 12 are hinged one to another by the 40 flexible sheet hinge 14 whereby the meeting faces may be separated along the longitudinal line 15. In this assembly the lower marginal edge of the shade 16 is placed between the meeting faces, the longitudinal serrations thereof acting to provide 45 a snubbing action which is supplemented to a further degree by the wrapping of the assembly around the exterior of the stiffeners 12. These strips may be held together by means of U-shaped clips at the ends of the stiffening strip or 50 by means of one or more screws 17 passing from one strip into the other.

Having described my invention, I claim:

1. The combination with a window shade of a stiffening strip overfolded, with the shade, along the lower edge thereof, and individual removable fastening elements attachable to said strip for holding the folds one against another.

2. The combination with a window shade of a stiffening strip comprising fibrous sheet material folded upon itself at least twice, the lower marginal portion of the said window shade being interposed between at least two of the folded layers, whereby a longitudinal edge of at least one of the layers exerts a snubbing action upon the sheet material to prevent detachment thereof from the stiffening strip.

3. The combination with a window shade of a stiffening strip constructed of fibrous sheet material of substantial thickness which is folded longitudinally upon itself at least twice, with the lower marginal portion of the shade being interposed between the folded layers of the stiffening strip, and means for holding the layers of the assembly 70 one against another.

4. The combination with a window shade of a stiffening strip constructed of fibrous sheet material of substantial thickness which is over-folded longitudinally upon itself at least twice, with the lower marginal portion of the sheet material being interposed between the over-folded layers of the stiffening strip, and means for holding the layers of the assembly one against another.

5. The combination with a window shade of a stiffening strip constructed of fibrous sheet material of substantial thickness which is over-folded longitudinally upon itself at least twice, with the lower marginal portion of the sheet material being interposed between the over-folded layers of the stiffening strip and means for holding the layers of the assembly one against another, comprising U-shaped clips embracing the outermost of the layers at the endwise portions of said strip.

6. The combination with a window shade of a stiffening strip, comprising at least two marginal sections folded one over another, the said window shade being disposed at opposite sides of one of the marginal over-folded sections, and means for holding said over-folded sections and window shade in the form of a folded roll.

7. The combination with a window shade of a

stiffening strip, comprising at least two marginal sections folded one over another, the said window shade being disposed at opposite sides of one of the marginal over-folded sections, and means for holding said over-folded sections and window shade in the form of a folded pile, comprising U-shaped clip members embracing the outer of said sections.
